UNITED STATES PATENT OFFICE.

HIRAM J. HOUGH, OF AKRON, OHIO, ASSIGNOR TO THE FIEBEGER HEATING COMPANY, OF AKRON, OHIO, A CORPORATION OF OHIO.

STOVE OR FURNACE.

No. 814,703.

Specification of Letters Patent.

Patented March 13, 1906.

Application filed July 27, 1905, Serial No. 271,488.

To all whom it may concern:

Be it known that I, HIRAM JAMES HOUGH, a citizen of the United States, residing at Akron, in the county of Summit and State of Ohio, have invented new and useful Improvements in Stoves or Furnaces, of which the following is a specification.

My invention has relation to the construction of combustion devices for stoves and furnaces; and the object of my invention is to provide a new and improved means for causing as nearly as possible a perfect and economical combustion of fuel therein, which will possess all the ordinary advantages of a direct draft to and through the fuel being consumed, as well as the additional advantage of supplying to the fuel an evenly-distributed and readily-regulated amount of oxygen to the sides of the mass of burning fuel, which will cause the complete and economical combustion of the same from the outside thereof, leaving the central portions of the fuel to gradually coke, thus permitting the fuel to give off its gaseous contents outwardly toward the walls of the combustion-chamber, whereby these gases become intermingled with the freshly-supplied oxygen from my improved means, causing the commingled fluids to burn with great intensity immediately in contact with the walls of the combustion-chamber, which are thereby more intensely heated than would be possible were the burning of the combined fluids to take place near the more central portions of said chamber.

The invention further aims to provide an ash-pit for the device provided with an outwardly-flaring upper portion to constitute an annular pocket and to seat within said outwardly-flaring portion a slotted ring member on which the fire-pot constituting a portion of the combustion-chamber may be supported and to admit air duly regulated as to quantity into the space formed by said outwardly-flaring portion of said ash-pit, whereby the same may pass through the slots in said ring-section and from there be distributed evenly and directly to the fuel sustained within the combustion-chamber.

The invention further aims to provide an effectual device for accomplishing the hereinbefore-mentioned objects which will be strong, serviceable, and readily handled and

in which the regulation of the amount of air supplied by the fuel may be easily controlled.

With the foregoing and other objects in view the invention consists of the novel construction, combination, and arrangement of parts constituting the device to be hereinafter referred to, and illustrated in the accompanying drawing, which forms a part of this specification, in which is shown the preferred embodiment of the invention; but it is to be understood that changes, variations, and modifications can be resorted to which come within the scope of the claims hereunto appended.

The drawing represents a central vertical section of my improved device.

In the drawing, 1 represents the ash-pit of a stove or furnace, which may be of any desired or preferred type and may (if deemed best) be provided with an inlet, (not shown,) as its construction may be of the common type, and its incorporation in the drawing will not add to the better understanding of this invention. It will be further stated that the description herein will be confined to furnaces, although the device (with very slight modifications) is fully capable of use in connection with heating-stoves. The upper portion of this ash-pit is provided with an outwardly-flaring annular pocket 2, and the top of this annular pocket 2 is provided with an annular groove 13 for a purpose to be stated.

At the point where the outwardly-flaring pocket 2 joins the main portion 1 of the ash-pit a curved shoulder is formed provided at suitable points with integrally-formed seats 3. The number of these seats 3 is immaterial, but it will be generally found that three is the best number to be employed. Arranged to rest upon these seats 3 is an annularly-formed member 4, having extending upwardly from its lower edge a series of slots which constitute between them a plurality of teeth 5, and the upper portion of this member 4 is further provided with an annular groove 6. At selected points in this member 4 the teeth 5 are integrally extended, thereby constituting a plurality of teeth 7 longer than the balance of the teeth 5. The elongated teeth 7 are so disposed and formed as to rest upon the seats 3, and thereby support the annular member 4 slightly above the shoulder

of the ash-pit in such a manner that the teeth 5, which constitute the main bottom edge of this member 4, are spaced apart from the shoulder sufficiently far to permit the ready 5 descent of ashes or other matter which might accumulate in the annular pocket 2.

Arranged to be seated in the groove 6, existing in the top of the annular member 4, is a fire-pot 8. This fire-pot 8 may be cylindrical 10 or outwardly flaring or shaped in the form of a frustum of a cone, as the requirements of the case may demand, and it is preferably further provided on its lower edge with a rabbet which will permit the balance of the bottom edge of the fire-pot 8 to enter the groove 6, leaving the inner face of the fire-pot to correspond and be in alinement with the inner face of the annular member 4.

The groove 6 in the upper portion of the 20 annularly-formed member 4 is of sufficient width to permit the perfect seating of the fire-pot thereon and also to permit the seating therein of a downwardly-turned edge of an annular cap or ring 9, which is adapted to 25 surround the fire-pot 8 and allow its outer downwardly-turned edge to seat in the groove in the top of the outwardly-flaring portion 2 of the ash-pit and cover the annular pocket existing between the outwardly-flaring portion 25 of the ash-pit and the annularly-constructed member 4, which supports the fire-pot 8.

It will be seen that the outwardly-flaring portion of the ash-pit 2, the cap or ring 9, and the annular member 4 of the combustion-chamber will constitute in connection with each other an annularly-formed air duct or pocket 10, which will surround the combustion-chamber of the device, and the air admitted to the annular air-duct 10 will escape therefrom through the slots in the member 4 existing between the teeth 5 thereof and unite with the fuel being consumed in the combustion-chamber surrounded by this member 4 and fire-pot 8.

In order to admit air and duly regulate the admission thereof to the annular air-duct 10, there is provided an inlet 11, preferably integral with the ash-pit, and further provided at 50 its outer end with a door or gate 12. This door or gate 12 will serve to regulate the amount of air which is admitted to the annular duct 10, and thus regulate the intensity of the combustion which is to take place within 55 the combustion-chamber of the device.

It will be obvious that the cap or ring 9 may be made in several sections or may be made as an integral article without in any manner departing from the nature of this invention, the main idea of which is to surround the combustion-chamber with an annular air-duct by which air may be admitted through the side walls thereof to the fuel contained therein. It will be further obvious 65 that air admitted to the ash-pit through the

inlet-door thereof will in addition to passing directly up through the fuel contained upon the grate of the device also pass laterally into the annular duct 10 and from thence through the slotted lower portion of the member 4 to 70 the fuel at or near its sides where the combustion is taking place.

It will readily be seen that any ashes or other matter which might be forced from the combustion-chamber through the slots in the 75 annular member 4 between the teeth 5 will fail to lodge upon the inner wall of the annular pocket 2 by reason of the curvilinear conformation imparted thereto, but will fall therefrom and descend into the main body of 80 the ash-pit 1.

What I claim, and desire to secure by Letters Patent, is—

1. The combination in a device of the class described, of an ash-pit provided at its upper 85 part with an outwardly-flaring annular portion forming with the main body of the ash-pit a shoulder, a slotted annular member arranged to seat on said shoulder and having means to sustain the fire-pot of the device, 90 the top of said annular member being spaced apart from the top of the outwardly-flaring portion of said ash-pit, and means to cover the space existing between them.

2. The combination in a device of the class 95 described, of an ash-pit provided at its upper part with an integral outwardly-flaring portion forming with the main body of the ash-pit at its junction therewith an annular shoulder, an annular member arranged to seat on 100 said shoulder having upwardly-extending slots in its lower portion, and means on its upper portion to sustain the fire-pot of the device, the top of said annular member being spaced apart from the top of the ash-pit, and 105 means to cover said space.

3. The combination in a device of the class described, of an ash-pit provided at its upper portion with an integral outwardly-flaring annular portion forming a shoulder at its 110 point of junction with the main body of the ash-pit, an annular member arranged to rest on said shoulder, having downwardly-extending teeth at its lower portion, and means at 115 its top for sustaining the fire-pot of the device, the top of said annular member being spaced apart from the top of the ash-pit, and means to cover said space.

4. The combination in a device of the class described, of an ash-pit provided at its upper portion with an integral outwardly-flaring annular portion forming with the main body of the ash-pit at its junction therewith an annular shoulder, an annular member provided 120 with downwardly-extending teeth in its lower portion, a plurality of said teeth being longer than the balance thereof, said elongated teeth being arranged to rest on the annular shoulder of said ash-pit and sustain said annular member, said annular member having at its 125 130

top means to sustain the fire-pot of the device, said top portion of said annular member and the top of said ash-pit being spaced apart, and means to cover said space.

5. The combination in a device of the class described, of an ash-pit provided at its upper part with an integral outwardly-flaring annular portion forming with the main body of the ash-pit at its junction therewith an annular shoulder, an annular member provided with downwardly-extending teeth in its lower portion, a plurality of said teeth being longer than the balance thereof, said elongated teeth being arranged to rest on said annular shoulder and sustain said annular member spaced apart from said shoulder, said annular member having means at its top for sustaining the fire-pot of the device, the top of said annular member being spaced apart from the top of said ash-pit, and means to cover said space.
10. The combination in a device of the class

described, of an ash-pit provided at its upper portion with an integral outwardly-flaring annular portion forming with the main body of the ash-pit at its junction therewith an annular shoulder, an annular member mounted on said shoulder and provided with means at its top to sustain the fire-pot of the device, the top of said annular member being spaced apart from the top of said ash-pit, means to 25 cover said space, and means to admit air to the space existing between said annular member and the outwardly-flaring portion of said ash-pit.

In testimony whereof I have hereunto set 30 my hand in presence of two subscribing witnesses.
